UNITED STATES PATENT OFFICE.

EUGENE A. KENNEDY, OF LEXINGTON, ILLINOIS.

OIL OR AIR OPERATED CROSSING SIGNAL.

Application filed March 1, 1924. Serial No. 696,270.

To all whom it may concern:

Be it known that I, EUGENE A. KENNEDY, a citizen of the United States, residing at Lexington, in the county of McLean and 5 State of Illinois, have invented certain new and useful Improvements in Oil or Air Operated Crossing Signals, of which the following is a specification.

This invention relates to oil or air operated crossing signal structures and it consists in the novel features hereinafter described and claimed.

An object of the invention is to provide a crossing signal structure in which the 15 parts are moved by oil or air which is confined in a pressure tank, there being means provided and operated by a passing train for pumping the oil or air into the pressure tank. A return or reservoir tank is provided in the system and after the oil or air 20 has been utilized for operating the signal, it is pumped by the passing train into the said reservoir tank.

A further object of the invention is to 25 provide in a signal structure, a post adapted to support the signal proper and within which compartments are provided and which constitute the pressure and reservoir tank for the storage, distribution and application of the oil or air.

In the accompanying drawings:—

Figure 1 is a top plan view of the crossing signal.

Figure 2 is a side elevation of the same.

Figure 3 is an enlarged fragmentary sectional view of the signal post and signal per se of the signal structure.

Figure 4 is a fragmentary side elevational view of the post.

Figure 5 is a transverse sectional view of 40 a pump mechanism used in the signal structure for returning the oil or air to the reservoir tank.

Figure 6 is a transverse sectional view of 45 the pump mechanism shown in Figure 5 and cut on a plane at a right angle to the plane of the section upon which Figure 5 is taken.

Figure 7 is a transverse sectional view of 50 a pump mechanism used in the crossing signal structure for passing the oil or air from the reservoir tank to the pressure tank.

As illustrated in the accompanying drawings, the railroad track is indicated at 1 and the vehicle crossing at 2. The signal comprises a post 3 which is erected at the side

of the track 1 and at the edge of the roadway 2 and which is provided at its upper portion with spaced plates 4 mounted upon pivoted levers 5. A sign plate 6 is mounted between the plates 4 and in the position 60 where the legend upon the plate 6 is normally concealed by the plates 4. A cylinder 7 is mounted upon the upper portion 3 and a piston 8 is slidably mounted in the cylinder 7. The piston 8 is provided with a relatively small opening 7' passing transversely therethrough. A pipe 9 is connected at its upper end with the cylinder 7 at a point above the upper surface of the piston 8. The lower end of the pipe 9 is connected 70 with the lower portion of the pressure chamber 9' provided in the upper end of the post 3. A pipe 10 is connected with the lower portion of the tank chamber 9' and is provided with a section disposed interiorly of 75 the post 3 and having a check valve 10'. At a point below the chamber tank 9', the pipe 10 enters the post 3 and extends downwardly toward the lower end thereof and is connected with a pump casing 11 located at 80 the side of one of the rails of the track 1. A reservoir tank or chamber 12 is provided within the post 3 at a point below the pressure chamber 9' and a pipe 13 communicates with the upper portion of the chamber 12. At its lower end, the pipe 13 connects with the pump casings 14 which are located one at each side of the post 3 and in the vicinity of one of the rails of the track 1. The pump casing 14 and the parts 85 carried therein are alike and will be described in detail hereinafter. A pipe 15 communicates with the bottom of the chamber 12 and passes down to the post 1 and connects at its lower end with the pump 90 casing 11 herebefore referred to. The pipe 15 is provided with a check valve 15'. A pipe 16 connects the lower end of the cylinder 7 with the pump casings 14. Assuming that a train is approaching the 100 signal post 3 and coming in the direction as indicated by the arrow in Figure 2, a trip, hereinafter to be described, and which is carried by the train, actuates the pump 14 whereby the oil or air is forced through the pipe 13 into the chamber 12 at the same time the pump 14 draws the oil or air through the pipe 16 from the cylinder 7 whereby the piston 8 begins to move in a 105 downward direction in the said cylinder. 110

In that the piston 8 is connected with the levers 5, the said levers 5 are swung whereby the plates 4 are lifted above the signal plate 6 and consequently a danger signal 5 is displayed at the crossing. From the chamber 12, the oil, or air passes through the pipe 15 and through the check valve 15' and enters the pipe 10. The oil or air moves past the check valves 10' in the pipe 10 and 10 enters the pressure tank or chamber 9'. From the tank or chamber 9', the oil or air is forced through the pipe 9 into the upper portion of the cylinder 7 and consequently pressure is applied to the upper surface of 15 the piston 8 and the said piston is caused to move promptly in a downward direction in the cylinder 7. The oil or air in the cylinder 7 and above the piston 8 may pass in a fine stream through the opening 7' in 20 the piston 8 and enter the lower portion of the cylinder 7 and pass through the pipe 16 as hereinbefore described.

When the train arrives at the pump casing 11, the said pump is actuated whereby 25 the oil or air is withdrawn from the pipe 10 and is passed into the chamber 12 and from the said chamber 12 may flow through the pipe 13 back to the pump casings 14. Thus the supply of oil or air through the 30 pipe 9 and from the chamber 9' is cut off and as the oil or air in the upper portion of the cylinder 7 passes through the opening 7' in the piston 8, the said piston 8 will move toward the upper end of the 35 cylinder 7 whereby the plates 4 are lowered over the plate 6 and the danger signal sign is concealed.

The pump mechanism 11 comprises a cylinder 12' which is connected with the pipe 40 sections 15 and 10 as shown in Figure 7, and the sections of the said pipe are provided with check valves 13' and 13'' located adjacent the end of the cylinder 12'. A piston 14' is slidably mounted in the cylinder 12'. A piston rod 15'' is connected at one end with the piston 14' and at its other end with the lower end portion of a ramp 16' which is pivotally mounted at the side of one 45 of the track rails 1 as shown in Figure 7.

50 The ramp lever 16' is provided with a head 17' which is disposed at the side of the rail 1. A spring 18' is connected at one end with the lower portion of the ramp 16' and at its other end with the casing 11 which 55 receives the lower portion of the ramp and the spring 18' is under tension with a tendency to hold the head 17' of the ramp 16' adjacent the side of the head of the rail.

As the train passes over the track 1, the 60 flanges of each wheel of the train will come in contact with the head 17' of the ramp 16' and force the said head 17' outwardly with relation to the track 1. The spring 18' returns the head 17' to its normal position 65 after having been encountered by the tire

of each wheel of the train. This movement on the part of the ramp lever 16' reciprocates the piston 14' in the cylinder 12' and the oil or air is pumped as hereinbefore described.

The casings 14 are located at points relatively remote from the roadway 2 and at the side of the track 1 a valve 21 is mounted upon the end of the pipe 13 and its stem 22 is connected with one end portion of an arm 70 or lever 23 which is pivoted in the casing 14.

The main stem of the lever 23 extends through the top of the casing and is disposed transversely across a stop member 24 which is mounted upon one of the rails of the track 1. A section 25 is pivotally connected with the upper end of the lever 23 by means of a rule joint 26 and the said section 25 is normally held in longitudinal alignment with the lever 23 by a spring 27 which is disposed across the pivot of the joint between the section 25 and the lever 23 as best shown in Figure 6 of the drawing. A cylinder 28 depends from the bottom of the casing 14 and a piston 29 is slidably mounted in said cylinder. The piston 29 is provided with a relatively small opening 30 which passes transversely through the said piston. The piston 29 is connected with an arm of the lever 23 by means of a rod 31. A lug 32 is mounted upon the pilot 33 of the locomotive which is adapted to travel over the track 1 and the section 25 of the lever 23 is disposed transversely across the path of movement of the lug 32.

Therefore when the locomotive carrying the pilot 33 approaches the section 25 of the lever 23, the lug 32 strikes the edge of the section 25 and swings the lever 23 in a direction away from the stop 24. Therefore 105 the upper end of the section 25 is swung downwardly and forwardly and in the direction in which the train is moving. A spring 34 is connected at one end with the lower portion of the lever 23 and at its other end with the casing 14 and as soon as the lug 32 clears the upper end of the section 25, the tension of the spring 34 comes into play and begins to return the lever 23 to its normal position as shown in Figure 6. On 110 the forward and downward swinging of the lever 23, the piston 29 is lowered in the cylinder 28 and the oil or air which is in the bottom of the cylinder passes through the opening in the piston and enters the upper 115 portion of the cylinder 28. In that the piston 29 is forced in a downward direction under the force of impact between the lug 32 and the section 25 of the lever 23, the piston 25 is moved in a downward direction 120 quickly, but inasmuch as the opening 30 is a small one, the volume of oil or air which accumulates in the upper portion of the cylinder 28 prevents the piston 29 from moving in an upward direction quickly.

Having described the invention, what is claimed is:

1. A crossing signal comprising a post provided with a reservoir chamber tank and a pressure chamber tank, a signal mounted upon the post, a cylinder mounted upon the post, a piston mounted in the cylinder and operatively connected with the signal, said piston having an opening passing transversely therethrough, a pipe connecting the pressure tank compartment of the post with the cylinder at a point above the piston, a ramp operated pump connected with the lower end of the cylinder for withdrawing fluid pressure from the cylinder, pipe connections connecting the ramp operated pump with the reservoir chamber, and pipe connections between the reservoir chamber and the pressure chamber.
2. A crossing signal comprising a post having a pressure tank compartment and a reservoir tank compartment, a signal mounted upon the post, a cylinder mounted upon the post, a piston slidably mounted in the cylinder and connected with the signal, a pipe connecting the pressure tank compartment with the cylinder at a point above the piston, a ramp operated pump connected with the lower portion of the cylinder for withdrawing fluid from the same, pipe connections between the ramp operated pump and the reservoir tank and between the reservoir tank and the pressure tank, and a ramp operated pump connected with the pipe connections between the reservoir tank and the pressure tank.

In testimony whereof I affix my signature.
EUGENE A. KENNEDY.
